(57) **CLAIM**

The ornamental design of a visual presenter, as shown and described.

DESCRIPTION

FIG. 1 is a perspective view of a visual presenter showing our new design;

FIG. 2 is a front elevational view of the visual presenter;

FIG. 3 is a rear elevational view of the visual presenter;

FIG. 4 is a left side elevational view of the visual presenter;

FIG. 5 is a right side elevational view of the visual presenter;

FIG. 6 is a top view of the visual presenter;

FIG. 7 is a bottom view of the visual presenter; and,

FIG. 8 is a reference view of the visual presenter.

According to an exemplary embodiment, the article of manufacture is a visual presenter as shown in the drawings.

According to an exemplary embodiment, a material of the visual presenter includes metal and/or synthetic resin.

According to an exemplary embodiment, the reference view in FIG. 8 is a perspective view of the visual presenter of which a camera supporter is further bent.

In the drawings, the broken lines represent portions of the visual presenter that form no part of the claimed design.
